PORTABLE DOG HOUSE

Anton C. Cliffgard, Wilmington, Calif., assignor to Robert K. Lee, doing business under the fictitious name of Best Container Company, Wilmington, Calif.

Filed Dec. 20, 1961, Ser. No. 67,994

Term of patent 14 years

(Cl. D12—2)

FIGURE 1 is a side elevation of a portable dog house showing my new design, the opposite side being a mirror image of this disclosed side;

FIGURES 2 and 3 are front and rear elevations, respectively, thereof;

FIGURES 4 and 5 are top and bottom plan views, respectively, thereof; and

I claim:

The ornamental design for a portable dog house, as shown and described.
